WEB PRINTING MACHINE

Harry V. Ball, Concord, Mass., assignor to Irving Trust Company, receiver in equity for R. Hoe & Co., Inc., New York, N. Y., a corporation of New York

Application June 23, 1933, Serial No. 677,321

8 Claims. (CL 270—5)

This invention relates to multi-unit web printing machines, and more particularly to newspaper printing presses.

In the production of the modern newspaper, provision must be made to meet the increasing demand for color pages and especially colored advertisements. Attempts have heretofore been made to supply color pages by providing selected printing units or printing couples of a newspaper press with color fountains so that a color page or color pages may be produced, or colored printing couples added to the press line or to an individual printing unit. Such arrangements are satisfactory within their limitations, but the progressively increasing demand for color pages in newspapers necessitates the provision of means affording maximum flexibility in the combinations of web runs.

It is the especial object of this invention to provide novel press arrangements and components, whereby color webs may be "worked" into a multiplicity of "runs" and conveyed to any selected folder or folders.

It is also an object of this invention to provide a novel press arrangement, whereby color webs may be "associated" with "perfected" black webs and the associated webs conveyed to any selected folder or folders.

Another object of the invention is the provision of novel press arrangement and components whereby color webs may be associated with the black newspaper webs with the maximum convenience and operating economy.

A more specific object of this invention is the provision of a novel press arrangement including a line of perfecting black units, folders located in the line and positioned to divide the line into separate cooperable groups of units, multi-color units laterally disposed relative to the line of units, and means for so associating the webs that a multiplicity of runs may be arranged and the webs conveyed to any desired folder or folders.

An additional object of the invention is the provision of novel press arrangement and components of generally improved construction whereby the resulting composite press will be simple, durable and inexpensive in construction, as well as practical, serviceable and efficient in its use.

With the foregoing and other objects in view, which will appear as the description proceeds, the invention resides in the combination and arrangement of parts, and in the details of con-

struction hereinafter described and claimed, it being understood that various changes in the precise embodiment of the invention herein disclosed may be made within the scope of which is claimed without departing from the spirit of the invention.

In the drawings:—

Figure 1 is a fragmentary diagrammatic plan view of a preferred press arrangement depicting a line of newspaper units with color units laterally disposed relative to the line,

Figures 2A and 2B combine to provide a composite diagrammatic side view of the press arrangement depicted in Figure 1, viewing the same from the color unit side of the line, the color units not shown,

Figure 3 is a diagrammatic sectional end view depicting one of the webs run through the color unit 26 to the line units and folder 16.

Figure 4 is a fragmentary diagrammatic plan view of the line of newspaper units depicting one of the possible web runs of the color web,

Figure 5 is a similar view depicting another web run of the color web, and

Figure 6 is a similar view depicting still another web run of the color web in which each web is slit into separate ribbons and each ribbon conveyed to separate folders.

Referring to the drawings, in which similar reference characters designate corresponding parts, there is shown a portion of a line of newspaper units, and, in the present instance, each unit comprises a first printing couple 12 and a superposed and offset perfecting couple 13, thus producing what is known in the art as a "Z type" newspaper unit, although it is to be understood that any preferred type of newspaper unit may be employed. In Figs. 1, 2A, 2B, 4, 5 and 6, a plurality of units designated as 11, 11a, 11b, 11c, 11d, 11e, 11f and 11g are shown in a line, but it is to be understood that any advantageous number of units may be employed, and preferably twelve units divided in separate groups, as hereinafter disclosed.

Double folders 16, 16a and 16b of the conventional newspaper type are provided in the line of units and positioned to divide the line printing units into groups of three units each, as clearly shown in Figs. 1, 2A, 2B, 4, 5 and 6. The folders and units comprising the printing line are operably supported by the usual framing including the sub-structure 17, conventional bed plate 18, press frames 19 and any preferred super-structure 20. The printing line units and folders are driven from any suitable source of

- power, preferably electric motors 21, through the conventional line shafting 22, bevel gears 23, upright shafts 24 from which power is imparted directly into the units 11, 11a, 11b, 11c, 11d, 11e, 11f, and 11g, and folders 16, 16a and 16b in any preferred or conventional manner but only here diagrammatically depicted. 80
- Multi-color printing units 26 and 26a are operably disposed at right angles to the line of units and supported by the conventional framing 27. Each multi-color unit includes a plurality of superposed printing couples 28 in vertical alignment and the unit is equipped with web guide rolls so that combinations of web runs are provided in this unit. 85
- The sub-structure 17 supports any preferred source of web supply for the units 11, 11a, 11b, 11c, 11d, 11e, 11f and 11g, and there is diagrammatically illustrated the conventional three roll paper supports or reels 31 and conventional tension belt or device 32 for each line printing unit. These paper rolls 33 are positioned below the units, as shown, and are located as near thereto as is possible consistent with operating convenience, as readily understood by those skilled in the art. 90
- Any preferred form of paper feed may be supplied for the multi-color units 26 and 26a, and, in the present instance, the sub-structure 17 supports the conventional two roll paper stand diagrammatically illustrated at 35 and any suitable tension device may be provided for these paper supply rolls. The web is led from the supply roll 36 through any preferred path of travel through the unit 26, then over the provided turner bar 40 to the press line, as will be hereinafter disclosed. The multi-color unit 26 is provided with a plurality of web guide rollers in order that any desired web run through the press may be provided, and the line of black perfecting units is also provided with rollers which are arranged to permit any desired combination of web runs to any selected folder or folders. 95
- Referring to Fig. 3, the web 37 from the selected roll 36 is led over web guide rollers 41 to the conventional feed rollers 42, then over rollers 43 through the uppermost printing couple 28 where one side of the web is printed, and this particular run is preferably colored, although black may be here employed if desired. From this point the web 37 is guided by rollers 44 through the remaining printing couples 28 of the unit 26 where four additional colors are printed on the opposite side of the web; or, if preferred, the first two couples 28 from the top of the unit may be employed to perfect the web in black, and three colors then applied to one side of the web. After passing through the unit 26, the web 37 is then guided over rollers 45, propellers 46, then over roller 47 to a turner bar 40 where this color web is turned through an angle of 90° and then run parallel to the web run of the line of perfecting units. In Figs. 2A, 2B and 4, one of the combination of web runs is depicted, and the web 37 after passing over the turner bar 40 is guided by rollers 50 to the drag roller 51 and down the former plate 52 to the selected folder 16. In the run here illustrated, a web 54 is guided by suitable rollers 55 from its supply roll 33, through the perfecting unit 11c and over guide rollers 56 and then associated with the color web 37, and finally over the drag roller 51 down the former 52 to the folder 16. A web 60 is led from its supply roll 33 through the perfecting unit 11b over suitable guide rollers 61, compensators 62, rollers 63 to the drag rollers 51 down the former plate 52 into the folder 16. A web 70 is guided from its supply roll 33 through the unit 11a over guide roll 71, around the drag roller 51 and down the former 52 to the folder 16. As shown in Fig. 2A, three additional webs 72, 73 and 74 are run over the drag roller 51, down the former 52 to the folder 16. These webs are run from the black perfecting unit 11 and two similar units (not shown) positioned in the line at the left of unit 11. 80
- As shown in Figs. 2B and 4, the web 37a is led from the color unit 26a over turner bar 40a around provided guide rollers 80, drag roller 81, down over former 82, and into the folder 16b. The web 85 is run from the unit 11d over suitable guide rollers 86, drag roller 81, down the former 82 to the folder 16b. Webs 88 and 89 from units 11e and 11f are similarly guided to the folder 16b, as clearly shown in Fig. 2B. Additional webs 90, 91 and 92 are led from the black perfecting line unit 11g and two similar units (not shown) located in the line at the right of unit 11g, into the folder 16b. 90
- Thus, it is seen, that six perfected black webs, four pages wide, and one color web of equal width, is run to the double folder 16, thereby producing twenty-four-page papers with one four-page color supplement when running non-collect, or forty-eight-page papers with two four-page color supplements when running collect. By slitting and turning the webs, a forty-eight-page paper with an eight-page color supplement can be produced running non-collect, cross-associate, as will be understood by those skilled in the art. This combination may be varied at will and the number of black pages increased and the color pages correspondingly decreased by printing one side of the color web black. 105
- Another arrangement of the color web run is depicted in Fig. 5, and in this run, the color web 37 from the color unit 26 and color web 37a from color unit 26a are led over turner bars 40 and 40a and then into the center double folder 120 16a. With this run there is produced eight-page color supplements with any selected number of black pages when employing both deliveries and running non-collect, or two eight-page color supplements when running collect. 125 By slitting and turning the color webs, a sixteen-page color supplement is produced and this arrangement may also be employed to produce separate color supplements by leading the two color webs 37 and 37a into the center folder 130 16a and "silencing" the black line units. 115
- In Fig. 6 an arrangement is shown which may be employed to divide the press in four sections of three black perfecting units, and the entire press driven as a unit, thereby producing a 135 four-page color supplement for each paper when running non-collect, or two four-page supplements for each paper when running collect.
- From the foregoing it will be readily understood that applicant has produced a novel press 140 arrangement and construction which permits extreme flexibility in the selection and association of webs to meet the requirement of present day color runs and permits economy in operation and maintenance of the press as well as conservation of production time. 145
- Having thus described my invention, I claim:—
1. In a web printing machine, the combination of a plurality of units in a line, each unit 150

- including a first printing couple and a perfecting printing couple, folders in the said line of units, and positioned to divide the line into separate cooperable groups of units, 5 printing units disposed at right angles to the said line of units, each of the angularly disposed units including in superposed relation a perfecting printing couple and a plurality of additional printing couples, a source of web supply located beneath the units, means positioned above the line of units for associating the webs of the angularly disposed units with the webs of the said line units, and common means for conveying the associated webs above the line units in either 10 direction or both directions along the line to the selected folder or folders. 2. In a web printing machine, the combination of a plurality of units in a line, each unit including a first printing couple and a perfecting 20 printing couple, folders in the said line of units and positioned to divide the line into separate cooperable groups of units, printing units disposed at right angles to the said line of units, each of the angularly disposed units including in superposed relation a perfecting printing couple and a plurality of additional printing couples, a source of web supply located beneath the units, and means positioned above the line of units for associating the webs of the angularly disposed 25 units with the webs of the said line units, and common means for conveying the associated webs above the line units in either direction or both directions along the line to the selected folder or folders located at either end or both 30 ends of a group of units. 3. In a web printing machine, the combination of a plurality of units in a line, each unit including a first printing couple and a perfecting printing couple, folders in the said line of units and positioned to divide the line into separate cooperable groups of units, printing units disposed at right angles to the said line of units, each of the angularly disposed units including in superposed relation a perfecting printing 40 couple and a plurality of additional printing couples, a source of web supply located beneath the units, means positioned above the line of units for dividing the webs from the angularly disposed units into separate ribbons, means for associating the ribbons with the webs of the line units, and means for conveying the separate 45 ribbons and associated webs in opposed directions along the line of units to separate folders. 4. In a web printing machine, the combination of a plurality of units in a line, each unit including a first printing couple and a perfecting printing couple, folders in the said line of units and positioned to divide the line into separate cooperable groups of units, printing units disposed at right angles to the said line of units, each of the angularly disposed units including in superposed relation a perfecting printing couple and a plurality of additional 55 printing couples, a source of web supply located beneath the units, means positioned above the line of units for dividing the webs from the angularly disposed units into separate ribbons, means for associating the ribbons with the webs of the line units, and means for conveying certain of the ribbons and associated webs in opposed directions to different folders, and for conveying other ribbons and associated webs in opposed directions to a common folder, thereby supplying to each folder a plurality of perfected black webs 60 and a color supplement. 5. In a web printing machine, the combination of a plurality of black perfecting printing units in a line, folders in said line of units and positioned to divide the line into separate cooperable groups of units, multi-color units disposed at right angles to the said line of units, a source of web supply located beneath the units, means positioned above the line of units for associating the webs of the angularly disposed units with the webs of the line units, and means for conveying the associated webs above the line units in either direction or both directions along the line of units to the selected folder or folders. 6. In a web printing machine, the combination of a plurality of black perfecting printing units in a line, folders in said line of units and positioned to divide the line into separate cooperable groups of units, multi-color units disposed at right angles to the said line of units, a source of web supply located beneath the units, means positioned above the line of units for associating the webs of the angularly disposed units with the webs of the line units, and means for conveying the associated webs above the line units in either direction or both directions along the line to the selected folder or folders located at either end or both ends of a group of units. 7. In a web printing machine, the combination of a plurality of black perfecting units in a line, folders in the line of units and positioned to divide the line into separate cooperable groups of units, multi-color printing units disposed at right angles to the line of units, each of the multi-color units including five superposed printing couples, a source of web supply located beneath the units, means for feeding a web to the upper printing couple of each multi-color unit to print on one side of the web, means for guiding the web downwardly between the remaining couples of the multi-color unit to thereby perfect the web and print additional colors on one side thereof and then upwardly over the unit, means positioned above the line of units for associating the webs of the multi-color units with the webs of the line units, and means for conveying the associated webs above the line units in either direction or both directions along the line of units to the selected folder or folders. 8. In a web printing machine, the combination of twelve black perfecting printing units in a line, three double-folders in the line of units and positioned to divide the line into four cooperable groups of three units to each group, two multi-color printing units disposed at right angles to the line of units and positioned laterally thereof, each of the multi-color printing units including five superposed printing couples, a source of web supply located beneath the units, means positioned above the line of units for dividing each web from the multi-color units into separate ribbons, means for associating these ribbons with the webs of the line units, and means for conveying certain of the ribbons and associated webs in opposed directions to different folders, and for conveying other ribbons and associated webs in opposed directions to a common folder, thereby supplying to each folder a plurality of perfected black webs and a color supplement.

HARRY V. BALL.
